DESIGN FOR A WHEEL

J Harold Hunt, Lansing, Mich., assignor to Motor Wheel Corporation, Lansing, Mich., a corporation of Michigan

Application August 7, 1933, Serial No. 48,944

Term of patent 7 years

To all whom it may concern:

Be it known that I, J Harold Hunt, a citizen of the United States, residing at Lansing, county of Ingham, State of Michigan, have invented a new, original, and ornamental Design for a Wheel, of which the following is a specification, reference being had to the accompanying drawing, forming a part hereof.

In the drawing:

Figure I is a side view of a wheel showing my new design;

Figure II is a perspective view of the wheel body shown in Figure I;

Figure III is an enlarged section taken on the line III—III of Figure I, and

Figure IV is a sectional view taken on the line IV—IV of Figure I.

I claim:

The ornamental design for a wheel as shown.

In testimony whereof he has affixed his signature.

J HAROLD HUNT.
